UNITED STATES PATENT OFFICE

2,113,750

TOY VEHICLE

Bert Travis, Whittier, Calif.

Application October 23, 1936, Serial No. 107,161

8 Claims. (Cl. 35—19)

My invention relates to a toy vehicle to be used as a play toy for children and of an educational character.

An object and feature of my invention in such a toy which is preferably a vehicle provided with wheels in which I provide a motor, a power transmission and a clutch inter-connecting the motor and the power transmission, therefore the child has under his control and operation the motor and the clutch by which a mechanical drive may be connected from the motor through the transmission to the driving wheels of the vehicle or the drive can be disconnected. In my arrangement I provide preferably a spring motor of the elastic band type which, when the clutch is in the closed position, the motor may be wound or tensioned by the child. In order to simulate the resemblance to the engine of a motor vehicle, the elastic band motor can only be tensioned by being wound in one direction. This is done by a pawl and ratchet arrangement, the pawl also retaining the winding means from a reverse motion. Then after the motor is wound the clutch may be released and a drive is effected from the rotor by the motor through a pulley type of transmission to the driving wheels. A further feature of my invention in regard to the pulley type of transmission is a connection showing a step up drive from the motor, this of course being a reverse from that of the ordinary automobile: in the toy a relatively slow rate of rotation of the rotor communicates a much higher rate of rotation to the driving wheels of the vehicle. Thus the child learns to understand the purpose of a change of speed ratio between the motor and the wheels of the vehicle.

Another feature of my invention is in mounting the pulley gear train in such a manner that the complementary sets of pulleys may be adjusted as to their distance apart in order to maintain a proper tension on the driving belts. This can be readily manipulated to drive with either loose or tight belts or with varying tensions in between. A further characteristic of the pulley transmission system is that this is pivotally mounted as an assembly in relation to the driving axle. A desired tension in the final drive belt from the last pulley of the transmission to a pulley on the driving axle is obtained by a resilient suspension of a free portion of the pulley transmission frame.

Considered in more detail the various characteristics of my invention comprise a vehicle body having a fixed axle with wheels rotatably mounted thereon and a driving axle, this being

provided with a driving pulley and with an automatic clutch which will only give a forward drive but not a reverse drive. The frame for the pulley drive speed ratio change gear includes a first vertical frame member pivotally mounted 5 on the live axle and preferably extending vertically therefrom. This carries one set of pulleys mounted on what may be considered as a counter-shaft. The main shaft is mounted on a second vertical frame which may be adjusted horizontally in relation to the first frame. This second frame has a series of small and large pulleys connected together and receives the direct drive by means of a belt from the rotor of the motor. Then by means of a series of belt connections, a step up speed drive is developed to the last pulley of the series on the main shaft. The drive belt from this last pulley to a pulley on the live axle also gives a step up. By the devices for varying the spacing between the counter-shaft and the main shaft the tension 10 on the belts between such pulleys on such shafts may be varied and the tension on the drive belt to the live axle is maintained by a spring connected between the fixed structure of the vehicle 15 and the floating or pivoted frame carrying the transmission.

A further object and feature of my invention resides in the elastic band motor in which I provide a tube or other suitable frame structure, 20 at one end of which I provide a rotatably mounted disc which may be turned by a crank, this having devices for attaching elastic bands thereto. The driving rotor is at the other end of the tube or frame and has a shaft with the first 25 driving pulley thereon. The rotor is provided with a disc to which the ends of the elastic bands may be attached. The first driving pulley is provided with a clutch so that when this clutch is in closed position the bands may be twisted 30 by rotating the first disc by the crank, this being prevented from reverse rotation by a pawl 35 and ratchet device.

My invention is illustrated in connection with the accompanying drawings, in which:

Fig. 1 is a side elevation of the vehicle partly broken away, taken in the direction of the arrow 1 of Fig. 2.

Fig. 2 is a vertical transverse section on the line 2—2 of Fig. 1 taken in the direction of the arrows.

Fig. 3 is a horizontal section on the line 3—3 of Fig. 1 in the direction of the arrows.

Fig. 4 is a vertical longitudinal section on the line 4—4 of Fig. 3 in the direction of the arrows.

Fig. 5 is a vertical transverse section on the line 5—5 of Fig. 3 in the direction of the arrows showing the pawl and ratchet on the winding end of the elastic band motor.

5 Fig. 6 is a detail plan in the direction of the arrow 6 of Fig. 2 showing the device for operating the clutch.

Fig. 7 is a perspective diagram of the pulley and belt drive.

10 In my invention I employ a vehicle body 11, preferably made of sheet metal and having a top 12, two sides 13 and a sloping front 14 and a more or less vertical back 15. A partition 16 near the back and an intermediate partition 17 may be 15 formed of frames or thin boards tacked or otherwise secured to the sides and top of the body structure. This leaves the body open at the bottom so that the various features of the drive mechanism may be inspected. A fixed axle 18 extends from side to side adjacent the rear and has wheels 19 rotatably mounted thereon. A live or driven axle 20 is also journaled in the sides 13 of the body and has the driving wheels 21 secured to this live axle. The live axle is shown at the 25 front of the vehicle. No provision is made for steering as the device is intended to have only a straight line direction of travel.

The elastic band motor designated by the assembly numeral 25 employs a tube 26 which is 30 fitted in an opening in the back wall 15 and extends through the center partition 17 to which it is secured. This has a reduced neck 27 at its forward end and a shoulder 28. A fixed plug 29 is fitted in the rear end of the tube, this having a 35 flange 30. The plug forms a bearing for a stub shaft 31 to which the winding disc 32 is connected, this disc being on the inside of the plug. A collar 33 has ratchet teeth 33' which are engaged by the pawl 34, mounted on the plug. A 40 slot 35 in the collar receives a pin 36 which extends through the shaft 31, thus assembling the collar, ratchet and disc 32 to the shaft and causing the collar to form a thrust bearing. A crank 37 having a handle 38 is attached to the outer 45 end of the shaft 31. The rotor or driving end of the spring motor designated 40 has a short shaft 41 journaled in the reduced neck 27. On the inner end of this shaft there is a disc 42 having a series of hooks 43. The elastic bands 44 are 50 stretched between the hooks 39 on the winding end of the motor and caught on the hooks 43 on the driving end. A drive pulley 45 is on shaft 41.

The transmission supporting frame designated by the assembly numeral 50 has a normally vertical frame panel 51, this having side uprights 52 with a bearing 53 on the driven or live axle 20. An upper cross bar 54 forms an upper connection and a middle bar 55 a middle connection between these side uprights. The complementary frame panel 60 employs upright side posts 61, a cross bottom connecting bar 62 and a top bottom connecting bar 63 (note particularly Figs. 1, 3, and 4). A telescopic connection 70 employs a pair of tubes 71 secured to the upper cross bar 54 of the frame 51 and a lower pair of tubes 72. Slidably mounted in each tube is a rod 73 for the top and 74 at the bottom. These are shown adjacent the uprights 52 and connect to the frame 60 adjacent the vertical side members 61 and the cross members 62 and 63. These rods are adjusted by set screws 75 which are threaded through the cross members 54 and 55 and press on the ends of the bars 73. The whole frame is maintained from turning on the axle 20 by means of a suspension spring 76 connected as at 77 to the frame 75

60 adjacent the top and at 78 to the partition 17 or other fixed structure of the vehicle.

The clutch 90 employs a plurality of lugs 91 on the outer face of the drive pulley 45 positioned to be engaged by a depressible rod 92 (note Fig. 5) which is slidably mounted in guideways 93 and 94 in the lower and upper cross bars 55 and 54. This rod is normally elevated by a lifting spring 95 bearing on the structure forming the guideway 93 and engaging a collar secured to the rod 92. An arch shaped cam 96 is secured to the upper end of the rod 92 and is exposed through a slot 97 in the top 12 of the body structure. This cam is engaged and actuated for depressing by a clutch arm 98 pivoted at 99 to the top 12 and having a handle 100. When the clutch is open for free transmission of power from the elastic band motor, the rod 92 is in its raised position due to the action of the spring 95 and the clutch arm 98 is positioned to one side of the slot 97. However moving this arm across the slot engages the cam end 96 on the rod 92 and causes a depression of the rod bringing it into a position to engage one of the lugs 91 on the pulley 45 which pulley rotates in the direction of the arrow 101 (note Figs. 2 and 7).

The assembly of the main shaft pulleys 110 utilizes a nonrotatable shaft 111 which is located in the frame 60 extending between the upright side posts 61. The counter shaft assembly 112 is 30 mounted in the frame 51 and extends between the upright bars or posts 52. Both of these may be formed of rods with nuts on the end.

The belt drive from the drive pulley 45 to the main shaft employs a belt 115 having guide lead 35 pulleys 116, 117 and 118 giving a change of direction to the first pulley 119 on the main shaft. The step-up pulley and belt drive employs a pulley 120 on the main shaft connected to the pulley 119 by a sleeve 121. A drive belt 122 leads to the 40 first pulley 123 on the counter shaft. A second pulley on the counter shaft 124 is connected to 123 by a sleeve 125 or these may be formed integral. A belt 126 leads to the third pulley 127 on the main shaft to which is connected the fourth pulley 128 on the same shaft. A belt drive 129 carries to the third pulley 130 on the counter shaft to which pulley is connected the fourth pulley 131 on the counter shaft by a sleeve or the like or being formed integral. A belt drive 132 leads to 50 the fifth pulley 133 on the main shaft.

The final drive 140 has a drive pulley 141 connected to the pulley 133 on the main shaft by a sleeve or being formed integral therewith. A belt 142 leads downwardly and forwardly to a loose 55 pulley 143 on the driven or live axle 20. An automatic clutch 145 employs a clutch sleeve 146 secured to the pulley 143 and a complementary clutch sleeve 147 fastened to the axle 20 by a set screw 148 or the like. These sleeves have complementary clutch jaws 149 arranged in the form of under-cut hooks with outside bevels 150. A light coil spring 151 on the axle 20 bears between one of the journals 53 and the pulley 143 tending to bring the clutch discs into contact. Manifestly these can only drive in one direction. In a reverse drive the bevels 150 thrust the hook jaws out of operating drive.

Various changes may be made in the details of the construction without departing from the 70 spirit or scope of the invention as defined by the appended claims.

I claim:

1. A wheeled toy having a driving axle with wheels, an elastic band motor having a winding 75

disc with elastic bands connected thereto and a pawl and ratchet to prevent reverse movement of said disc, a rotor having the other ends of the bands connected thereto, a pulley connected to the rotor having a plurality of stop lugs connected thereto, a clutch rod slidably mounted, a spring maintaining the rod out of contact with the said lugs, a cam end on the rod, a clutch arm pivotally mounted on part of the vehicle to engage the said cam and to position one end of the rod to engage the lugs to prevent rotation of the said pulley and a belt and pulley drive from the pulley of the rotor to the said driving axle.

2. A wheeled toy as claimed in claim 1, the belt and pulley drive including a belt and pulley transmission having a frame with a first panel pivotally mounted on the driving axle and a second panel slidably mounted on the first panel, a spring connected between the second panel and a fixed part of the vehicle, one of the panels having a main shaft mounted therein, the other panel having a countershaft, pulleys of varying sizes on the main and the countershafts with belt connections for the pulleys and a final drive from one of the said shafts to the axle.

3. In a wheeled toy vehicle a belt and pulley transmission including a first and a second panel, an adjustable telescopic connection to space said panels, a main shaft on one panel, a counter shaft on the other panel, a belt and pulley change speed having interconnecting pulleys on both shafts, a spring motor, an initial drive from the motor to one of the pulleys of the transmission, a final drive from another pulley of the transmission to one of the wheels of the vehicle.

4. In a wheeled toy vehicle as claimed in claim 3, the telescopic connection of the panels comprising a plurality of tubes connected to one panel, rods connected to the other panel fitting therein and adjusting screws extending inwardly from one end of the tubes, each to engage the end of a rod to thereby vary the tension on the belts between the pulleys on the main counter shafts.

5. In a wheeled toy vehicle, a driving axle having wheels thereon, a change speed transmission mounted in a frame pivoted to the said axle, a spring secured to one portion of said frame and a fixed structure, a spring motor, an initial drive from the spring motor to the transmission mounted in the frame, a final belt drive from a pulley mounted in the frame to a pulley on the axle. 5

6. In a wheeled toy vehicle, a driving axle having wheels, a transmission frame having a first panel pivoted to the axle, a second panel, a telescopic connection between the first and the second panel, a spring connected between the second panel and a fixed part of the vehicle, one of the panels having a main shaft, the other having a 10 counter shaft, each with a series of pulleys forming a belt and pulley transmission train, the pulleys on the two shafts being connected by belts, a spring motor, an initial drive from the motor to a first driven pulley on one of the shafts, a final 15 belt drive from the last pulley of the belt and pulley transmission train to a pulley on the axle. 20

7. In a wheeled toy vehicle as claimed in claim 6, a clutch comprising a collar connected to the pulley on the axle, the said pulley being loose 25 thereon, a complementary collar secured to the axle, said collars having interlocking jaws positioned to give a drive in one direction only.

8. In a wheeled toy vehicle, the combination of a spring motor having a rotor with a pulley with 30 a plurality of lugs thereon, a slidably mounted clutch rod, means to normally elevate said rod to bring its lower end out of the path of the said lugs, the rod having a cam shaped upper end, the vehicle having a top with an opening therein, said 35 end being adapted to project through said opening, a clutch arm pivoted to the top and movable over said opening to engage the cam end of the said rod and depress the said rod into a position for its lower end to engage the said lugs and a 40 transmission drive from the said pulley to at least one of the wheels of the vehicle.

BERT TRAVIS.
